ERASER HOLDER

Ten Eyck T. Mosher, Peacedale, Glenmont, N. Y.

Application April 14, 1936, Serial No. 74,347

3 Claims. (Cl. 120—36)

The invention relates to an eraser and more especially to an eraser holder.

The primary object of the invention is the provision of a holder of this character, wherein a 5 disk type of typewriter eraser can be conveniently and easily supported for the holding thereof so that such eraser will work upon paper in a typewriter or for service in erasing anything needing the same, that is, for the erasing of freshly done 10 typewriting, old typewriting, printing, writings in ink and lead pencil, the removal of dirt and finger marks from papers and books, particularly where the erasing requires pressure for a clean and neat job and without injury to the fingers and 15 hand of an operator.

Another object of the invention is the provision of a holder of this character, wherein the disk type of eraser can be conveniently and easily fastened in place and such eraser will be firmly 20 held against rotation or turning while in use and such disk eraser can be conveniently adjusted in the holder to present a fresh surface of the eraser to the work when the same is required yet when such eraser is in action it will not turn in the 25 holder, thereby enabling the easy erasure of matter through the use of said eraser.

A further object of the invention is the provision of a holder of this character, wherein the disk type of eraser can be held in the holder by 30 a fastener such as a winged nut carrying bolt and when carried by said holder enables the use of the eraser with ease and dispatch, relieving strain ordinarily required when manipulating the eraser proper and avoiding bruised skin, cut 35 fingers or fatigue incident to the holding of the eraser by the fingers, the holder being of novel construction.

A further object of the invention is the provision of a holder of this character, which is extremely simple in construction, thoroughly reliable and efficient in operation, readily and easily handled, strong, durable, and inexpensive to 40 manufacture.

With these and other objects in view, the invention consists in the features of construction, combination and arrangement of parts as will be hereinafter more fully described, illustrated in the accompanying drawing, which discloses the preferred embodiment of the invention and 45 pointed out in the claims hereunto appended.

In the accompanying drawing:

Figure 1 is a perspective view of the holder constructed in accordance with the invention shown grasped by the hand of a user and the 50 eraser carried thereby.

Figure 2 is a sectional view on the line 2—2 of Figure 1 looking in the direction of the arrows.

Figure 3 is a side elevation of the holder with the eraser removed.

Figure 4 is a view similar to Figure 3 showing the disk type of eraser fitted in the holder with the whisk brush eliminated.

Similar reference characters indicate corresponding parts throughout the several views in the drawing.

Referring to the drawing in detail, particularly Figures 1 to 3 inclusive, the holder comprises an elongated stock forming a handle-like body 5 preferably made from hard wood although it may be made from metal or any other suitable material and is cut and shaped at one end portion to provide a handle 6 proper, the latter having a hole 7 therethrough so that the holder can be suspended from a nail or other fastener upon a wall or support.

The body 5 remote from the handle end 6 thereof at one side is cut into to provide a counter-seat 8, it having a shape to accommodate a disk-like rubber eraser 9 so that a portion of the peripheral edge as at 10 of the said eraser 9 will 20 be exposed for service in making erasures from paper, cardboard or the like and when such paper may be held within the typewriter, although the erasures can be made very successfully when the paper, cardboard or other material is entirely 30 away from the typewriter machine. This disk as is usual is held within a forked bearing 11 carrying a whisk brush 12 and centrally of the bearing 11 is a suitable opening which matches the hole 13 provided in the body 5 so as to receive a bolt 35 14 carrying a winged nut 15 whereby the eraser can be secured seated and firmly held in the counterseat 8, and carried by the holder for service rather than to have the eraser supported in the hand between the fingers thereof as is customary.

The counterseat 8 in the body 5 is continued to form an abutment shoulder 16 against which can be placed the bearing 11 in the fastening of the eraser in the holder, as is clearly shown in 45 Figure 1 of the drawing.

In Figure 4 of the drawing there is shown a modified form of eraser 17, it being cheeked by a metallic disk 18 and such eraser 17 is fastened in place by a fastener 19 as should be clearly 50 apparent.

An essential feature in having the eraser carried by the holder permits the firm fastening of the eraser so that it will not rotate or turn while in use in the holder, whether such eraser is being 55

manipulated either for ordinary use or real strenuous erasing. Yet by the loosening of the fastener the eraser will turn to a new position and then be ready when firmly fastened for further service.

5 What is claimed is:

1. A holder for a disk eraser having a whisk brush comprising a body having a counterseat in one face thereof at one end and a handle at the opposite end, a fastener carried by the body at the counterseat for the detachable securing of a disk-like eraser within said counterseat, and a shoulder at the forward end of the body next to the counterseat for abutment of a whisk brush bearing for said eraser therewith.
- 10 2. In combination, a holder comprising a handle having a substantially circular recess in the forward end thereof, said recess opening through a side of said handle and also opening through one edge of the handle and the forward end thereof, a disk-shaped eraser seated in said recess and having a portion thereof projecting through the opening in said one edge and forward end of the handle, and means securing said eraser in said recess.
- 15 3. In combination a handle having a substantially circular recess in the forward end thereof, said recess opening through a side of said handle and also opening through one edge of the handle and the forward end thereof, a disk-shaped eraser seated in said recess and having a portion thereof projecting through the opening in said one edge and forward end of the handle, means securing said eraser in said recess, a brush, and mounting means for mounting said brush on said eraser, 10 said mounting means engaging against the forward end portion of said handle in a manner to hold said brush at an obtuse angle to the length of the handle.
